(57) **CLAIM**

The ornamental design for an inflatable perfusion enhancement structure, as shown and described.

DESCRIPTION

FIG. 1 is a top view of an inflatable perfusion enhancement structure showing our design in an uninflated state.

FIG. 2 is a bottom view thereof.

FIG. 3 is a front view thereof.

FIG. 4 is a rear view thereof.

FIG. 5 is a right side view thereof.

FIG. 6 is a left side view thereof.

FIG. 7 is a perspective view of the inflatable perfusion enhancement structure of FIGS. 1-6 in an inflated state positioned in a first suitable environment; and,

FIG. 8 is a perspective view of the inflatable perfusion enhancement structure of FIGS. 1-6 in an inflated state positioned in a second suitable environment.

The broken lines in FIGS. 1-6 depict portions of the inflatable perfusion enhancement structure that form no part of the claimed design. The additional broken lines shown in FIGS. 7-8 in the form of a bed and chair, respectively, depict environmental subject matter and form no part of the claimed design.

1 Claim, 6 Drawing Sheets
